Watney, E. J. May
Lever, M. Taylor. R. Campbell.

United States Patent Office.

ROBERT R. CAMPBELL, OF LOWELL, MASSACHUSETTS, ASSIGNOR TO LOWELL
MANUFACTURING COMPANY.

Design No. 2,909, dated February 4, 1868.

DESIGN FOR A CARPET-PATTERN.

The Schedule referred to in these Letters Patent and making part of the same.

TO ALL WHOM IT MAY CONCERN:

Be it known that I, ROBERT R. CAMPBELL, of Lowell, in the county of Middlesex, and State of Massachusetts, have originated and designed a new Pattern for Carpets or other fabrics, of which the following is a full, clear, and exact description, reference being had to the accompanying drawings, making part of this specification.

This design is composed of irregular-shaped set figures and small sprig-work, as shown in the drawing.

The colors employed for the different portions of the design may be varied to suit the taste and wish of the manufacturer.

Claim.

What I claim as my invention, and desire to secure by Letters Patent, is—

The design or pattern for carpets or other fabrics herein set forth.

R. R. CAMPBELL.
